J. G. SNYDER & J. YOUNG.
CORN PLANTER.

No. 10,583.

Patented Feb. 28, 1854.

UNITED STATES PATENT OFFICE.

JOHN G. SNYDER AND JOSEPH YOUNG, OF WHEATFIELD TOWNSHIP, PERRY COUNTY, PENNSYLVANIA.

IMPROVEMENT IN SEED-PLANTERS.

Specification forming part of Letters Patent No. 10,583, dated February 28, 1854,

To all whom it may concern:

Be it known that we, JOHN G. SNYDER and JOSEPH YOUNG, of Wheatfield township, in the county of Perry and State of Pennsylvania, have invented a new and useful Improvement in Corn-Planters; and we do hereby declare that the following is a full, clear, and exact description of the construction and operation of the same, reference being had to the annexed drawings, forming part of this specification, in which—

Figure 1 is a plan of the machine. Fig. 2 is a side elevation of the same. Fig. 3 is a vertical longitudinal section of the hopper, showing the feeding arrangement. Fig. 4 is a top view of plate B. Fig. 5 is a top view of plate I. Fig. 6 is a top view of frame marked X. Fig. 7 is a view of sliding section b. Fig. 8 is a section on line x y of Fig. 3. Fig. 9 shows the mouths of the tubes e f g under the slide b. Fig. 10 is a plan of the lower revolving plate, O.

Similar letters in the several figures refer to the same part of the machine.

Our invention consists in constructing a corn-planter the principal elements of which shall consist of a rotary plate, perforated with feeding-cells, which, passing under a brush, deposit their contents either through a single tube for hill-planting or by single grains successively in different tubes, the lower plate being formed with a movable section, so that the mouths of the several tubes may be either closed or opened, so as to operate in either of the cases above mentioned. Connected with this portion of the machine is an arrangement for insuring the regularity of the deposit of the grain by the opening of the lower extremity of each tube immediately after the grain has been dropped into it. The feeding-plate is made sloping toward the center, so that whatever grains may be forced under the brush shall pass through an opening in the frame into a bucket provided for catching such stray grains. Attached to the machine is an elastic cover so arranged with springs as not to be liable to breakage in meeting with obstructions to its progress.

In the drawings, A is the hopper, having the inclined bottom B, perforated with the cells a in sets of three, which bottom has a

rotary motion by reason of the cogs N under the hopper meshing into the pinion C on the shaft D. This shaft is revolved by the forward motion of the driving-wheel E through the movable pinion F on the shaft D, which meshes into one of the cogged circles H H' on the plate G, according to the velocity with which it is required to revolve the feeding-plate B.

Below the revolving plate B is the bottom plate, I, in which is the sliding section b, (seen in Figs. 5 and 7,) making when in the position shown by Fig. 5 the three apertures c c' c'' for the successive dropping of the grain, and when as seen in Fig. 7 forming but a single opening, d, through which three grains can pass at one time to the dropping-tube.

Below the bottom plate, I, and under the openings shown in Fig. 5, are three tubes, e, f, and g, two of which are shown in Fig. 3. These tubes are partly inclosed within the mold-board J, as shown in Fig. 3. Behind these tubes runs the shaft L, having on its upper extremity the pinion M, meshing into the cogs N under the hopper. At the lower extremity of this shaft is the plate O, with a single aperture, coinciding successively with each of the openings of the tubes e f g, as seen in Fig. 8.

In rear of the planting apparatus is the elastic covering-bow P, so arranged by the spring Q and arm R as to pass over obstructions which might injure or destroy an arrangement of a less yielding character.

Within the hopper is the brush j for preventing more than a single grain from each cell from passing to the tubes, and in the side of the frame is the opening k, which, by reason of the inclination of the feeding-plate B, forces any grains which may accidentally pass under the brush into the bucket S in the center of the machine.

The ungearing apparatus consists of the lever T and plate U, supporting the rear extremity of the shaft D, the withdrawing of the lever permitting the cog-wheel C to fall and stop the revolution of the plate B.

The operation of our planter is as follows: The pinion F is adjusted to mesh into the cogged circle on the plate G, which will give the required velocity of the feeding-plate B.

and the sliding section *b* of the lower plate, *I*, arranged with regard to the number of grains to be dropped at a time, both of the adjustments depending upon whether the grain is to be planted in hills or in drills. Should the former be required, the pinion *F* is moved to mesh with the smallest circle, *H'''*, and the section of the lower plate placed in the position shown in Fig. 7. For drilling the reverse arrangement takes place, as we then require the plate *B* to rotate rapidly and the successive apertures *c c' c''* to be opened, so that an almost continuous stream of grain shall be kept up. After these adjustments the grain is thrown in the hopper and the machine driven forward. The cells *a* each receive a grain of corn, and by the rotation of the plate *B* are successively carried under the brush *j* and over the apertures in the lower plate, *I*, (seen in Figs. 5 and 7,) when they discharge their contents into the tube or tubes, as the case may be. Now, were the grains to pass directly through the tubes to the furrow, their times of deposit would be irregular by reason of some grains striking against the sides of the tube one or more times. To remedy this defect we introduce the bottom plate, *O*, with the single aperture, rotated by the cogs under the hopper, so that the opening passes regularly and in succession under the outlets of the tubes *e f g*, thus, if the machine be used for drilling, depositing each grain at the proper distance from its predecessor, and if used for hill-planting making all the hills the same distance apart. The aperture in the plate *O* passing under the mouth of each tube an instant after the fall of the grain insures the dropping at regular intervals, the pinion *M* being the proper size to perform its revolution in the time between the passage of the sets of apertures *a* over the discharging-openings in the bottom plate, *I*. After the grain has been deposited, as above described, the elastic bows *P*, passing after, cover the grain in an effectual manner,

the spring *Q* preventing the breaking of this portion of the machine by giving way when the bows come in contact with an obstacle.

The advantage of our planter consists partly in the regularity with which the planting is performed and the facility with which the planter can be changed from a drilling to a hillling machine. The arrangement of the plate *O* passing under each of the tubes *e f g* in succession, immediately after the fall of the grain through them, it is readily seen, furnish the means of depositing the corn in the furrows with the utmost regularity with respect to distance. The arrangement for disposing of the stray grains which force themselves under the brush is also of great importance, and the manner of covering well worthy of attention. As for the detailed advantages of this machine, the simplicity of its arrangement is such that to any one at all acquainted with machines of this nature they will readily suggest themselves upon an examination of this specification.

What we claim as our invention, and desire to secure by Letters Patent, is—

1. The sliding section *b* in the bottom plate, *I*, in combination with the tubes *e f g* and revolving perforated plate *O*, as described, for rendering the machine capable of hill or drill planting at pleasure, and insuring a regularity of deposit, as herein fully set forth.

2. The aperture *k* in the frame *X*, in combination with the inclined form of the plate *B* for carrying off the surplus grains and collecting them in the bucket *S*, substantially as specified.

In testimony whereof we have hereunto signed our names before two subscribing witnesses.

JOHN G. SNYDER.
JOSEPH YOUNG.
